US00D961984S

(12) **United States Design Patent** (10) **Patent No.:** **US D961,984 S**
(45) **Date of Patent:** **** Aug. 30, 2022**

(54) **GRILL**

(71) Applicant: **Home Depot Product Authority, LLC**,
Atlanta, GA (US)

(72) Inventors: **Dan Williams**, Arlington Heights, IL
(US); **Riley Wong**, Arlington Heights,
IL (US); **Jason Carley**, Arlington
Heights, IL (US); **Steve Oshgan**,
Arlington Heights, IL (US)

(73) Assignee: **Home Depot Product Authority, LLC**,
Atlanta, GA (US)

(**) Term: **15 Years**

(21) Appl. No.: **29/729,433**

(22) Filed: **Mar. 26, 2020**

(51) LOC (13) Cl. **07-02**

(52) U.S. Cl.

(74) *Attorney, Agent, or Firm* — Greenberg Traurig, LLP

(57) **CLAIM**

The ornamental design for a grill, as shown and described.

DESCRIPTION

FIG. 1 is a perspective view of our new design for a grill in an expanded configuration;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and

FIG. 8 is a perspective view of our new design for a grill in a collapsed configuration;

FIG. 9 is a front elevation view thereof;

FIG. 10 is a rear elevation view thereof;

FIG. 11 is a left-side elevation view thereof;

FIG. 12 is a right-side elevation view thereof;

FIG. 13 is a top plan view thereof; and,

FIG. 14 is a bottom plan view thereof.

The broken lines illustrate portions of the grill that form no part of the claimed design.

1 Claim, 13 Drawing Sheets
